UNITED STATES PATENT OFFICE.

A DOLPHE WENGER, OF PARIS, FRANCE.

FLUID-PRESSURE RAILWAY-BRAKE.

SPECIFICATION forming part of Letters Patent No. 253,139, dated January 31, 1882.

Application filed September 28, 1881. (No model.) Patented in France December 28, 1880.

To all whom it may concern:

Be it known that I, ADOLPHE WENGER, a citizen of the French Republic, residing in Paris, France, have invented certain Improvements in Apparatus for Working Railway-Brakes by Fluid-Pressure, (the same having been patented to me in France by Letters Patent No. 140,385, dated December 28, 1880,) of which invention the following is a specification.

This invention relates to the construction and arrangement of apparatus for working brakes on railway-trains by fluid pressure, the chief objects aimed at being to render the action of the brakes rapid and certain, to maintain them in action as long as may be necessary, to regulate the braking force as desired, and to bring the brakes into action automatically in case of accident to the train or to the apparatus. The pressure employed may be either that of compressed air or the excess of the atmospheric pressure above that of rarefied air. The following description applies in the former case, it being understood, however, that by suitable inversion of valves and other parts the apparatus could be arranged for vacuum action.

For working by compressed air the apparatus is arranged as follows: An engine-pump 30 on the locomotive compresses air in a reservoir. From this reservoir, in which, for the sake of compactness, the pressure may be very high, a pipe leads the air at reduced but still considerable pressure throughout the train, the reduction of pressure being effected by a reducing-valve worked by a differential piston, on the smaller area of which the reservoir-pressure acts, tending to open the valve, while the pressure in the train-pipe acts on the larger 40 area, tending to close the valve. From the first train-pipe thus supplied a branch communicates, through another reducing or regulating valve, with a second train-pipe, this regulating-valve having a piston connected to a spring, the tension of which is adjustable by a hand-screw, so that any desired reduction of pressure may be effected and maintained in the air supplying the second train-pipe. The two train-pipes, as they pass under each carriage of the train, cross each other, so that at each end of the carriage one of the pipes al-

ways presents itself to the same hand, and thus no mistake can occur in coupling each length to the next. The first or higher pressure-pipe is continued throughout the train 55 without stop-cocks or other interruptions, its end at the last carriage being closed by a blank half-coupling. The second or lower pressure-pipe has a stop-cock at each end of every carriage, which stop-cock is kept opened while 60 the train is made up, but can be closed when the carriages are to be separated. On each carriage are fixed two brake-cylinders, one for each pair of wheels, or one double cylinder. The brake-piston is in each case of differential 65 area, its one side having a trunk by which it is linked to the brake-levers. This trunk has a shoulder, which, when the piston is at the extreme of its outstroke, seats on packing as a valve, preventing leakage. The outer end of 70 the cylinder (which extends some distance beyond the piston at its extreme stroke) communicates by a branch pipe and check-valve with the higher-pressure train-pipe, and the inner end of the cylinder communicates by a branch 75 pipe and valve-box with the lower-pressure train-pipe, the latter valve-box having a valve governing an outlet-passage. This valve is worked by a piston subject to the pressure in the branch pipe, and the piston is made 80 with a small hole or groove, or it may be a small spring-valve, allowing passage of air enough to maintain equal pressure on both sides of the piston under ordinary circumstances, but not enough, when the pressure 85 in the second train-pipe is suddenly reduced, either voluntarily or in consequence of accident, for the purpose of putting on the brakes, in which case the piston is moved so as to open the outlet-valve, permitting the air 90 to escape directly from the inner end of each brake-cylinder, the air in the outer end of the cylinder being in each case retained by the check-valve. The lever worked by each brake-piston projects from a rocking shaft, which has 95 short arms carrying the brake-blocks for the one side of each pair of wheels, and other arms linked to a similar rocking shaft carrying the brake-blocks for the other side, so that when the brake-piston moves inward both sets of 100 blocks are pressed against the wheels, clamping them between them, and when the piston

moves outward the blocks are released. As the blocks are poised on the arms which carry them, springs are provided in these arms to keep the upper ends of the blocks from touching the wheels when the brakes are off.

- The action of the apparatus is as follows: As long as the pressures in the two train-pipes are such that the lower pressure, acting on the full area on the inner side of each brake-piston, 5 balances, or nearly so, the higher pressure, acting on the smaller annular area on its outer side, the brakes are held off by weights or springs; but when the pressure in the second train-pipe is reduced so that the brake-pistons are subjected to greater outside pressure, these move in, putting on the brakes with a force depending on the difference of pressure in the two pipes, which difference can be varied at will by means of the regulating-valve on the locomotive, 10 the braking force being thus under complete control. In the event of fracture or separation of the second train-pipe, the pressure in it being thus reduced, the brakes become automatically applied; and should the first train-pipe be opened by the same accident, the escape of air from it does not interfere with the action of the brakes, as the check-valves prevent escape from the outer ends of the brake-cylinders. The outlet-valves in the branches 15 leading to the inner ends of the brake-cylinders insure rapidity of action in putting on the brakes, as they permit direct escape of air from each cylinder when the pressure in the second train-pipe is lowered, and thus no time is lost, such as would be occupied if the issuing air had to traverse a considerable length of pipe 20 before escaping. It is of advantage to provide stop cocks in the branches from the train-pipes to the brake-cylinders and their valves, so that 25 in case of any of these being deranged they can be excluded from the system.

In the accompanying drawings, Figure 1 is a side view, and Fig. 2 a plan, showing the arrangement on a locomotive of the engine-pump P , the high-pressure reservoir R , charged with air compressed by the pump P , and communicating by the pipe A with the reducing-valve D , and thence by a branch furnished with a stop-cock, r , with the high-pressure pipe A extending along the train. A branch from A , after passing the reducing-valve D , leads through the second reducing or regulating valve, C , to the second train-pipe, B , which is also provided with a stop-cock, r' , and with another, r'' , used 55 when the locomotive is separated from the train.

Fig. 3 is a side view, Fig. 4 an end view, and Fig. 5 an inverted plan, showing the arrangement of the pipes and brake-gear on each 60 brake-carriage. The pipes A and B are crossed, so that each presents itself to the same hand at each end of the vehicle. The pipe B has at each end a stop-cock, r'' , which is kept open while the train is made up, but may be closed 65 when the vehicles are to be separated.

The brake-cylinder F (shown on an enlarged

scale in one form by the longitudinal section, Fig. 6, and in a modified form at Fig. 7) has two pistons, K K , and side ports, a^2 a^2 , for admitting air under pressure to put on the brakes, 70 and a port, b^2 , for pressure to take them off. When the pistons are at the extreme of their outstroke, packings e' in the one case and j^2 in the other case prevent leakage around their rods or trunks.

The cup-leather j' of Fig. 7 is shown to an enlarged scale at Fig. 8, embraced by a caoutchouc ring, k' , to press it tightly against the trunk of the piston. In the construction shown in Fig. 6 small pistons P' are employed, 80 instead of trunks working through stuffing-boxes.

Fig. 9 shows a similar single-acting cylinder with one piston. When the rod L , connecting the piston with the brake-levers, extends 85 into the piston, and is jointed thereto to give freedom of lateral movement, it may be connected as shown at Fig. 10, the rod L' being jointed to the piston by a pin at o' , and the hole for the pin being closed by a screw, v' , 90 with a packing-washer, j^2 . Each brake-cylinder F may be disconnected from the train-pipes A and B by closing stop-cocks r^3 r^4 in the communicating branches a' b' .

Fig. 11 is a vertical section of the reducing-valve D . It is fitted with two pistons, p and p' , of different areas, having their common rod M connected to the valve S . The branch c communicates with the high-pressure reservoir R , and the branch c' with the train-pipe A and regulator-valve C . The pressure in the latter is reduced in proportion as the area of the piston p' exceeds that of p .

Figs. 12 and 13 are sections of the regulator-valve C , shown in two different positions. The cylindrical body of the valve-box is divided by partitions into four compartments, d d' d^2 d^3 , and through packings in these partitions works a plunger, I , connected by a rod, e , passing through a boss, g' , to a head, i' , within a helical spring, g , which can be extended or compressed by a hand-screw, i , working in a nut, h , attached to the spring. The compartment d communicates with the train-pipe A , the two compartments d' and d^3 communicate with the train-pipe B , and d^2 communicates with an escape-aperture, Z . The left end of the plunger I is thus always subject to the pressure in A , and the right end to the pressure in B . If no force be exerted by the screw i , the piston I 110 will be pressed toward the right, admitting air from A to B till the pressures, including that of spring g , come to equilibrium. If by means of the screw i the plunger be drawn toward the left, as shown in Fig. 13, air will escape from B through d^2 and Z until the pressure in B is so far reduced that the superior pressure in A overcomes the tension of the spring g . Thus there is always maintained in the train-pipe B a pressure less than that in 115 A by the amount that is due to the tension of the spring g , as determined by the driver work.

ing the hand-screw *i*, the braking force throughout the train being thus adjusted as required by the driver. Should the pipe *B* give way, the brakes are put on by the superior pressure in the parts of the brake-cylinders communicating with *A*. Should the pipe *A* give way, then the piston *I* of the regulator-valve will move to the left, as shown in Fig. 13, and the pipe *B* will become discharged through the aperture *Z*, having the same effect of putting on the brakes by the reduction of pressure between the pistons of the brake-cylinders.

Fig. 14 shows a modified construction of the regulator-valve, in which a slide, *l*, is used to govern ports leading respectively to *B* and *Z*, the slide-case being in communication with *A*, so that the pressure in *A* acts on the under side of a piston, *I*, attached to the slide, while the pressure in *B*, communicated through a passage, *k*, acts on the upper side of *I*, which is subject to the force of the spring *g*, adjusted by the screw *i* and handle *m*. The brake-cylinder *F* is connected to the pipes *A* and *B* through two interposed valve-boxes, *G* and *G'*, as shown in the transverse section, Fig. 15. The check-valve box *G* is shown by two sections at right angles to each other at Figs. 16 and 17. It is divided by a partition having through it a hole, *o*, covered by a valve, *n*. Under the valve the box communicates by the branch *a* with the train-pipe *A*, and above the valve it communicates by a branch, *a'*, with the ports *a²* *a²* of the brake-cylinder *F*. Thus compressed air can pass from *A* to *F*, but the valve *n* closes against its return. *p* is a stop-cock for blowing out moisture.

The escape-valve box *G'*, Fig. 15, is shown in vertical section at Fig. 18. It contains a piston, *t*, having its rod *p* attached to the escape-valve *q*, and having small holes *r* at its lower end. While the valve *q* is seated air can pass from the train-pipe *B* through the holes *r* to the port *b²* of the brake-cylinder *F*. When, by reduction of pressure in the train-pipe *B*, the pressure communicated from the brake-cylinder forces the piston *t* upward, the holes *r* are closed; but the valve *q* is opened, allowing immediate escape from the middle of the brake-cylinder, so that the brakes are put on. The arrangement of the brakes themselves is shown in Figs. 3 and 4. Each brake-block *S* has two side cheeks, *a'*, inclosing the suspending-rod *b²*, which is jointed at *c'* to the under frame of the vehicle and at *o'* to the brake-block. If the brake-blocks could turn freely on the pins *o'*, they might, when the brakes are off, touch the wheels. To prevent this the joints at *o'* are stiffened, as shown by the section to an enlarged scale at Fig. 19, stiff springs *d'* being inserted in holes of the hangers *b²*, to bear hard against the cheeks *a'* of the brake-blocks. Thus constructed, the brake-blocks do not turn on their axes when they move away from the wheels, but on the axes or points of suspension of the rods *b²*. It is of advantage to provide, as shown in Fig. 15, a pipe, *t'*, connecting the

train-pipes *A* and *B* with a stop-cock, *r⁶*, by opening which and closing *r³* the one pipe *B* may be used alone. When the train is made up all the stop-cocks in the several lengths of pipe *B* are open. In separating a train, so as to introduce other cars before uncoupling the lengths of *B*, the stop-cocks next to the point of separation should be closed, in order to maintain the pressure in the pipe, and not opened until the pipes are coupled, as, if some of the stop-cocks should negligently be left closed, the brakes behind them would be inoperative. The proper condition of the cocks, when the train is made up, should thus be tested.

The operation of my system of brakes is as follows: The air in the pipes *A* and *B* being under high and low pressures, respectively, as before described, the engine-driver, when he wishes to apply the brakes, turns the screw *i* of the valve *C* in such direction as to distend the spring *g* and connect the pipe *B* with the outlet *Z*, whereupon more or less of the air in *B* escapes, reducing the pressure therein and in the cylinders *F* between the two pistons *K* *K* sufficiently that it can no longer resist the pressure of the air from the pipe *A* on the smaller area of the opposite sides of the pistons, whereupon the two pistons are forced toward each other, and the brakes are thus applied. The force with which the brakes are applied is determined by the extent to which the driver has opened the valve *C* and the time he has left it open. The instant the pressure between the pistons falls sufficiently the valve *q* in the casing *G'* opens and permits the remaining air to escape, thus causing the brakes to be quickly applied. When the brakes are to be taken off, the driver turns the screw *i* of the valve *C* in the opposite direction, and thereby admits compressed air from the pipe *A* into the pipe *B* until the pressure in the latter becomes sufficient to force the pistons *K* *K* apart and throw off the brakes.

Having thus described the nature of this invention and in what manner the same is to be performed, what I claim as new, and desire to secure by Letters Patent, is as follows:

1. A railway-car provided with a cylinder, a differential piston therein, a pipe communicating with said cylinder on the side of said piston of least area, another pipe communicating with said cylinder on the side of said piston of greatest area, the said pipes extending from end to end of the car, and connections between said piston and the brake-shoes, combined substantially as set forth, whereby, when the pressure against the side of the piston of greatest area exceeds by more than the difference of area the pressure on the opposite side, it moves the piston and applies the brakes.

2. The combination, with a railway-car and its brakes, of a brake-applying mechanism consisting of a cylinder, a differential piston therein, a pipe extending from end to end of the car, a connection between said pipe and the cylinder on the side of the piston of greatest area,

a branch from said pipe connecting with said cylinder on the side of the piston of least area, and a check-valve in said pipe, substantially as set forth.

5 3. A locomotive provided with an air-compressing pump, a reservoir arranged to receive the compressed air therefrom, a pipe leading from said reservoir extending to the rear of the locomotive and provided with a coupling at its 10 end, and a reducing-valve in said pipe, consisting of a differential piston controlling a cut-off valve, combined and arranged substantially as set forth, whereby a high pressure in the reservoir generates a proportionately less pressure 15 in the pipe beyond the valve.

4. The combination of a source of compressed air on the locomotive, an air-pipe leading thence through the train and communicating with cylinders on the cars, the said cylinders, differential pistons therein, and a second pipe, connected also to said cylinders on the opposite side of said pistons, extending to the locomotive, and there connected with a source of compressed air through the medium of a valve under the control of the engineer, whereby the latter may control the pressure in the said 25 second pipe, substantially as set forth.

5. The combination of cylinder F, differential piston K, pipes A and B, and escape-valve G', substantially as set forth.

30 6. The escape-valve G', consisting of the cas-

ing, the plunger t therein, holes r r in said plunger, and valve q, operated thereby, in combination with pipe B and cylinder F, substantially as set forth.

35

7. The combination of the differential piston K, provided with an axial rod or plunger, with a cylinder, F, having a stuffing-box through which the said rod or plunger passes out, and a washer of packing substance arranged inside 40 the cylinder, around said rod or plunger, where it enters said stuffing-box, whereby, when the brakes are off and said piston is forced toward the washer and a shoulder on the piston compresses said washer, the latter supplements the 45 stuffing-box and more effectually prevents the escape of air, substantially as set forth.

40

8. The combination of the car-wheels, brake-applying mechanism, hanger b², brake-shoe S, having cheeks a' a', embracing said hanger, pin 50 o', jointing said shoe to said hanger, and springs d', inserted in sockets in the hanger and bearing against the cheeks of the shoe, substantially as set forth.
